UNITED STATES PATENT OFFICE.

MERVIN M. BLACK, OF HUMPHREY, NEW YORK, ASSIGNOR TO MINNIE BLANCHE BLACK, OF DEWEY, OKLAHOMA.

SUPPORTING DEVICE.

No. 892,800.

Specification of Letters Patent.

Patented July 7, 1908.

Application filed November 18, 1907. Serial No. 402,704.

To all whom it may concern:

Be it known that I, MERVIN M. BLACK, a citizen of the United States, residing at Humphrey, in the county of Cattaraugus and 5 State of New York, have invented certain new and useful Improvements in Supporting Devices; and I do hereby declare the following to be a full, clear, and exact description of the invention, such as will enable others 10 skilled in the art to which it appertains to make and use the same.

My invention relates to new and useful improvements in supporting devices and more particularly to that class adapted to be 15 used for holding nursing bottles and my object is to provide means for adjustably securing the device to a cradle, buggy, or other article employed for holding infants.

A further object is to provide means for 20 supporting the nursing bottle in position to be reached by the infant.

A still further object is to provide means for adjusting the bottle-holding means at various angles and at different heights and a 25 still further object is to provide means for securing the bottle in position on the supporting device.

Other objects and advantages will be hereinafter referred to and more particularly 30 pointed out in the claims.

In the accompanying drawings which are made a part of this application, Figure 1 is a side elevation partly in section of my improved supporting device. Fig. 2 is a sectional view as seen on line 2—2, Fig. 1, and, 35 Fig. 3 is a detail perspective view of the lower end of the bottle-supporting arm.

Referring to the drawings in which similar reference numerals designate corresponding 40 parts throughout the several views, 1 indicates a standard, to the lower end of which is secured a clip 2, the upper end of said clip having a socket 3, in which the end of the standard 1 is introduced and the standard is held 45 therein by means of a binding screw 4. The clip 2 is adapted to fit over parts of the object to which the supporting device is to be attached and is held in position thereon by means of a locking bolt 5, said bolt being 50 threaded and introduced through a threaded opening in one arm of the clip and has secured to its inner end a disk 6, said disk being loosely mounted on the bolt 5, so that the disk may remain stationary while the bolt is 55 rotated.

The upper end of the standard 1 is preferably bent downwardly and outwardly to form a shank 7, to the extreme outer end of which is secured a ball 8 and coöperating with said ball is a socket 9, carried at one end of a 60 finger 10. The socket 9 is adapted to be turned on the ball 8, so as to dispose the finger 10 at various angles and in order to hold the finger in any pre-determined position, a set screw 11 is directed through the wall of 65 the socket 9 and into engagement with the periphery of the ball.

One end of a supporting arm 12 is entered through an opening 13 in the outer end of the finger 10 and is adjustably secured 70 therein by means of a set screw 14, whereby the lower end of the arm 12 may be adjusted at various distances from the finger and securely held in its adjusted position. The lower portion of the arm 12 is slightly curved 75 and the extreme lower end thereof is bent upwardly and formed into an eye 15, said eye forming a support for the closed end of a bottle having a tube secured thereto, as shown in Fig. 1 of the drawings and adapted to receive the neck of a bottle when the nipple is attached directly to the neck, as shown in Fig. 3 of the drawings. The bottle is supported in position on the curved portion of the arm 12 by means of a rack or frame 16, 80 85 said rack being preferably formed of wire and secured to the arm in any preferred manner, as by looping portions of the rack around the arm. After the arm 12 has been properly adjusted, the bottle is placed in position on 90 the rack 16 and, when a tube is used in connection with the bottle, the closed end of the bottle is placed against the eye 15 and the bottle firmly held on the rack by securing a locking pin 17 to the arm 12 and introducing 95 the same around the neck of the bottle, while, when the bottle is provided with a nipple, the neck of the bottle is introduced through the eye 15, which will serve to hold the bottle in position on the rack.

The supporting device is adapted to be secured to various articles and it will be seen that the parts of the support may be readily adjusted to place the bottle in reach of the infant. It will further be seen that by forming the device of separable parts, it may be readily folded to occupy but a small space, so that it can be transported from place to place. It will likewise be seen that when the bottle is properly secured on the rack, the 110

infant cannot displace the same, and, thereby, dispensing with the services of an attendant.

What I claim is:

- 5 1. A supporting device of the class described, comprising a standard, means to adjustably secure said standard to an object, a finger, means to movably secure said finger to the standard, an arm adjustably secured to said finger the lower end of said arm being curved and means to support a bottle on said arm and additional means to hold the bottle in position on the supporting means.
- 10 2. A supporting device of the class described, comprising a standard, means to adjustably secure the standard to an object, a shank on said standard, a finger, means to movably secure the finger to the shank, a supporting arm, means to adjustably secure the supporting arm to the finger, an eye at the lower end of said arm and means to support a bottle on said arm.
- 15 3. A supporting device of the class described, comprising a standard, a clip removably secured to said standard, means to
- 20
- 25

clamp the clip in engagement with an object, a shank on said standard, a ball at the end of said shank, a finger having a socket adapted to receive said ball, means to adjust the socket on the ball, a supporting arm adjustably secured to said finger, an eye at the lower end of said arm and a rack on said arm adapted to support a bottle.

4. A supporting device of the class described, comprising a standard, means to secure said standard to an object, a finger, means to adjustably secure the finger to the standard, a supporting arm adjustably secured to the finger, a rack on said arm and a locking pin carried by the arm adapted to surround the neck of a bottle and secure the bottle in position on said rack.

In testimony whereof I have signed my name to this specification in the presence of two subscribing witnesses.

MERVIN M. BLACK.
